MINING MACHINE

Original Filed June 6, 1923

UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

MINING MACHINE

Original application filed June 6, 1923, Serial No. 643,617. Divided and this application filed June 23, 1925. Serial No. 39,127.

My invention relates to mining machines and more particularly to mining machines of the flexibly fed type.

An object of my invention is to provide an improved mining machine. Another object of my invention is to provide a mining machine of improved and compact construction especially adapted to use in thin veins of coal. A further object of my invention is to provide an improved feeding mechanism for mining machines. Other objects and advantages of my invention will hereinafter more fully appear.

This application is a division of my co-pending application Serial No. 643,617, filed June 6, 1923.

In the accompanying drawings I have shown for purposes of illustration one form which my invention may assume in practice.

20 In these drawings,—

Fig. 1 is a plan view partially in section of a mining machine constructed in accordance with the illustrative embodiment of the invention.

25 Fig. 2 is a side elevation of the machine shown in Fig. 1.

Fig. 3 is an end elevation of the feeding end of the machine.

30 Fig. 4 is a longitudinal section on the line 4—4 of Fig. 1.

In its illustrative embodiment my invention is disclosed in the form of an air propelled flexibly fed mining machine of the longwall type comprising a frame 1 adapted to slide along a mine bottom upon its bottom surface 2 and carrying a cutter bar 3 which is pivotally connected to the frame 1 and adapted to be held in different angular positions with respect thereto in a well known manner, the bar preferably occupying a position at right angles to the major dimension of the frame 1 during cutting and the frame 1 moving longitudinally along a face with the bar at the rear end thereof. The 45 machine is moved during cutting by feeding mechanism generally designated 4 which will hereafter be more fully described.

The body of the machine comprises a motor section 5, a feed section 6 and a cutter bar 50 carrying section 7, the feed and cutter bar

carrying sections being disposed at opposite ends of the motor section and rigidly connected to the latter.

Within the motor section 5 is a fluid pressure actuated motor 8 herein illustrated as 55 comprising a pair of intermeshing tooth rotors 9 and 10 suitably secured as by keys 11 to shafts 12 and 13 respectively and enclosed in bores 14 in the section 5. The shafts 12 and 13 are journaled in heads 15 and 60 16. Fluid is supplied to the motor through a pipe connection 17 controlled by a throttle valve 18. It is to be understood that the motor described and shown may be replaced by other motors of the pressure fluid or electric type. 65

The cutting mechanism includes a cutter bit carrying cutter chain 19 supported for circulation about the periphery of the cutter bar 3 and actuated through suitable driv- 70 ing connections by a worm wheel 20 which is rotated by a worm 21 carried upon and driven by a longitudinally extending shaft 22 extending between the worm wheel 20 and one side of the machine frame. The shaft 75 22 carries a gear 23 which is driven by a pinion 24 mounted upon an appropriately journaled shaft 25 disposed at the central longitudinal line of the machine. The shaft 25 carries a gear 26 with which pinions 27 80 and 28 splined to the extremities of the shafts 12 and 13 and longitudinally slidably along the latter are alternatively connectible to effect rotation of the gear 26, and so of the pinion 24, in opposite directions. The connection of the pinions 27 and 28 with gear 85 26 is controlled by a handle 29 at the forward end of the machine frame through suitable connections not shown. Cutter bar 3 is rigidly connected to a turntable 30 and 90 is provided with projections 31 and 32 in which a hook may be secured to effect swinging of the bar. The bar may be locked in adjusted position by a pin 33 carried by the frame section 7. From the description 95 it will be noted that the machine may cut with either side of the frame 1 next to the working face, the cutter chain being adapted to be actuated in opposite directions through the pinions 27 and 28 and the bits 100

34 with which the cutter bar is provided being reversible in the links of the cutter chain.

Now taking up the feeding mechanism, it will be observed that a shaft 35 is mounted in standards 36 at the rear end of the frame and in a horizontal position midway between the sides of the frame. Rotatably mounted upon the shaft 35 is a gear carrying sleeve member 37 having a spur gear 38 arranged at the forward end thereof and having also formed thereon a conical friction surface 39. The shaft 35 at its opposite end is provided with a threaded portion 40 with which a hand rotatable nut 41 cooperates. Between the nut 41 and the gear 38 is arranged a double drum structure 42 journaled as at 43 upon a sleeve-like portion 44 of the member 37 and providing a relatively large drum portion 45 and a small drum portion 46 adapted to receive cables as later described. A ball bearing 47 is arranged between the nut and an annular shoulder 48 upon the member 42 and permits the nut 41 to transmit pressure to the member 42 to force a conical friction surface 49 thereon into frictional engagement with the conical friction surface 39 upon the member 37 without tendency to rotate the nut, and the flange 50 also secured to the member 42 permits the nut upon opposite rotation to retract the member 42 and break the friction connection between the surfaces 39 and 49. A pinion 51 mounted upon a shaft 52 suitably journaled in the section 6 engages the gear 38 and is adapted to drive the same. The shaft 52 is driven by a worm wheel 53 secured thereto and rotated by a worm 54 rotatable upon a vertical axis and driven by a ratchet wheel 55 and pawl 56. The pawl 56 is carried upon an arm 57 which rocks about the axis of the worm 54 and the pawl carrier is oscillated about its axis of pivotal movement by a rod 58 connected to an eccentric pin 59 carried upon a disk 60 which is rotatable with a worm gear 61. The latter is also mounted for rotation upon a vertical axis. The rod 58 may be adjusted in lengths by means of a threaded connection 62 between its ends. The eccentric pin 59 may be adjusted radially relative to the axis of the crank disk 60 to vary the angular movement of the rocker arm 57 and consequently the speed of rotation of the ratchet wheel 55. It is obvious that the ratchet and pawl and eccentric mechanism described permits a wide adjustment in the speed of rotation of the worm 54. A worm 65 is rotatable with a shaft 66 supported in bearings 67 in alinement with the rotor shaft 12 with which shaft the shaft 66 is suitably connected in driven relation.

A cable 68 is wound upon the drum 45 and a cable 69 upon the drum 46, the former being used for effecting feeding movement of the machine along the face during cutting

and being arranged in a single or double strand connection as desired, depending upon the speed of machine movement wanted. The cable 69 is adapted to be used to swing the bar, being provided with a hook or other suitable means not shown for engagement with the projections 31 or 32. To guide the cables suitable guide sheaves or rolls 70, 71, 72 and 73 are arranged in pairs at opposite sides of the rear end of the machine, the rollers 70 and 72 being adapted to cooperate with the cable 69 without rewinding of the latter when it is desired to extend the cable down along either side of the machine frame to effect swing of the bar and the sheaves 71 and 73 being adapted to cooperate with the cable 68 without rewinding of the latter upon its respective drum, dependent upon which side of the machine frame is next the coal. Carried on the rear end of the feed frame are members 75 with which a hook 76 upon the extremity of the cable 68 may be connected.

In the operation of the illustrative form of the invention the machine is brought to a position adjacent the face of the coal and, depending upon the direction in which it is desired to cut, with one side or the other of the frame 1 next to the working face. The cable 69 is then led forward, passing around the sheave 70 or 72, and connected to the member 31 or 32, which is the nearer to the face. Adjustment of the nut 41 causes frictional engagement between the surfaces 39 and 49 and upon fluid supply to the motor 8 the cable 69 may be drawn in, swinging the bar about its pivotal axis. The cutter chain is simultaneously driven in the proper direction through one of the pinions 27 or 28 and when the bar has been swung to a right angle position beneath the coal the pin 33 may be used to lock it in the desired position. The rate of bar swing may be controlled by varying the pressure employed in forcing the surfaces 39 and 49 into frictional engagement. At the conclusion of this operation the cable 69 may be removed or wound upon the drum 46 and have its extremity suitably attached to prevent unwinding. Cable 68 is then led about the sheave 71 or 73, which is adjacent the face, and around a pulley secured to an anchor jack at a point spaced from the front end of the machine frame, and is then brought back and hooked over one of the members 75. The motor is again started and the machine advances along the face of the coal at a slow or cutting speed, the speed being variable by the friction clutch or by adjusting the crank pin 59 toward or away from the center of the disk 60. It is obvious that any other suitable means may be used for varying the throw of the pawl as desired. It will be observed that the construction illustrated provides a very low and compact arrangement of parts, the disposition of the drum upon a longitudinally ex-

tending axis permitting the shortening of the machine frame by a substantial amount.

While I have in this application specifically described one form which my invention may assume in practice, it will be understood that this form of the same is shown for purposes of illustration and that the invention may be modified and embodied in various other forms without departing from its spirit or 10 the scope of the appended claims.

What I claim as new and desire to secure by Letters Patent is:

1. In a mining machine, in combination, a horizontal motor, a feed operating member rotatable on a horizontal axis extending longitudinally of the machine and adapted to cooperate directly with flexible feeding means, and operative driving connections between one end of said motor and feed operating member for transmitting rotation to the latter at a cutting speed including a plurality of worms and a variable speed transmission mechanism between said worms, one of said worms being driven by said other worm 25 through said transmission mechanism.

2. In a mining machine, in combination, a horizontal motor, a feed operating member rotatable on a horizontal axis extending longitudinally of the machine and adapted to 30 cooperate directly with flexible feeding means, and operative connections between one end of said motor and feed operating member including a plurality of worms one of which rotates on an axis parallel to the axis 35 of rotation of said feed operating member and a variable speed transmission mechanism between said worms, one of said worms being driven by said other worm through said transmission mechanism.

3. In a mining machine, in combination, a motor, a feed operating member rotatable on a horizontal axis extending longitudinally of the machine and adapted to cooperate directly with flexible feeding means, and operative connections between one end of said motor and feed operating member including a plurality of worms one of which rotates on a vertical axis and a variable speed transmission mechanism between said worms, one 50 of said worms being driven by said other worm through said transmission mechanism.

4. In a mining machine, in combination, a motor having a power shaft, a feed operating member rotatable on a horizontal axis 55 extending longitudinally of the machine and adapted to cooperate directly with flexible feeding means, and operative driving connections between one end of said motor and feed operating member for transmitting rotation to the latter at a cutting speed including a plurality of worms one of which is coaxial with said motor shaft and a variable speed transmission mechanism between said 60 worms, one of said worms being driven by

said other worm through said transmission mechanism.

5. In a mining machine, in combination, a motor having a power shaft, a feed operating member rotatable on a horizontal axis 70 extending longitudinally of the machine and adapted to cooperate directly with flexible feeding means, and operative driving connections between one end of said motor and feed operating member for transmitting rotation to the latter at a cutting speed including a plurality of worms one of which is coaxial with said motor shaft and a variable speed transmission mechanism between said worms, one of said worms being driven by 75 said other worm through said transmission mechanism, said feed operating member rotating on an axis parallel to the axis of rotation of said motor shaft.

6. In a mining machine, in combination, a feed operating member rotatable on a horizontal axis extending longitudinally of the machine and adapted to cooperate directly with flexible feeding means, and operative driving connections between one end of said 80 motor and feed operating member for transmitting rotation to the latter at a cutting speed including worms at opposite sides of said machine and a variable speed transmission mechanism between said worms, one of 85 said worms being driven by said other worm through said transmission mechanism.

7. In a mining machine, in combination, a feed operating member rotatable on a horizontal axis extending longitudinally of the 90 machine and adapted to cooperate directly with flexible feeding means, and operative driving connections between one end of said motor and feed operating member for transmitting rotation to the latter at a cutting speed including worms at opposite sides of 95 said machine, and variable speed power transmitting connections between said worms, one of said worms being driven by said other worm through said transmission mechanism.

8. In a mining machine, in combination, a motor, a feed operating member adapted to cooperate directly with flexible feeding means, and operative driving connections between said motor and feed operating member 100 for transmitting rotation to the latter at a cutting speed including worms at opposite sides of said machine, and ratchet and pawl mechanism between said worms.

9. In a mining machine, in combination, a motor, a feed operating member rotatable on a horizontal axis and adapted to cooperate directly with flexible feeding means, and driving connections between said motor and feed operating member including ratchet 105 and pawl mechanism including an oscillating pawl carrier whose plane of oscillation is parallel to the axis of rotation of said feed operating member.

10. In a mining machine, in combination, 110

- a motor, a feed operating member rotatable on a horizontal axis and adapted to cooperate directly with flexible feeding means, and driving connections between said motor and feed operating member including ratchet and pawl mechanism including an oscillating member whose plane of oscillation is parallel to the axis of rotation of said feed operating member.
11. In a mining machine, in combination, a motor, a feed operating member adapted to cooperate directly with flexible feeding means and rotatable upon a horizontal axis extending longitudinally of the machine, and operative driving connections between said motor and feed operating member including a ratchet and pawl mechanism including a member oscillating in a horizontal plane.
12. In a mining machine, in combination, a motor, a feed operating member adapted to cooperate directly with flexible feeding means and rotatable upon a horizontal axis extending longitudinally of the machine, and operative driving connections between said motor and feed operating member including ratchet and pawl mechanism including a member oscillating in a horizontal plane above the plane of rotation of said feed operating member.
13. In a mining machine, in combination, a horizontal motor having its casing slidable directly on its bottom on the mine bottom, the height of the motor substantially determining the height of the machine, a feed operating member adapted to cooperate directly with flexible feeding means and rotatable on a horizontal axis extending longitudinally of and lying in the central longitudinal vertical plane of the machine, and operative driving connections between said motor and feed operating member including a plurality of worms through which said feed operating member is driven and a friction clutch between said worm gearing and said feed operating member.
14. In a mining machine, in combination, a horizontal motor having its casing slidable directly on its bottom on the mine bottom, the height of the motor substantially determining the height of the machine, a feed operating member adapted to cooperate directly with flexible feeding means and rotatable on a horizontal axis extending longitudinally of and lying in the central longitudinal vertical plane of the machine, and operative driving connections between said motor and feed operating member including a plurality of worms through which said feed operating member is driven, one of which rotates on an axis parallel to the axis of rotation of the feed operating member and a friction clutch between said worm gearing and said feed operating member.
15. In a mining machine, in combination, a horizontal motor having its casing slidable directly on its bottom on the mine bottom, the height of the motor substantially determining the height of the machine, a feed operating member adapted to cooperate directly with flexible feeding means and rotatable upon a horizontal axis lying midway between the sides of the machine, and operative driving connections between said motor and feed operating member including a plurality of worms arranged respectively at opposite sides of said axis and through which said feed operating member is driven and a friction clutch between said worm gearing and said feed operating member.
16. In a mining machine, in combination, a horizontal motor having its casing slidable directly on its bottom on the mine bottom, the height of the motor substantially determining the height of the machine, a feed operating member adapted to cooperate directly with flexible feeding means and rotatable upon a horizontal longitudinally extending axis lying midway between the sides of the machine, and operative driving connections between said motor and feed operating member including a plurality of worms arranged respectively at opposite sides of said axis and through which said feed operating member is driven and a friction clutch between said worm gearing and said feed operating member.
17. In a mining machine, in combination, a motor, cutting mechanism driven from one end of said motor, a feed operating member rotatable on a horizontal axis and adapted to cooperate directly with flexible feeding means, and operative driving connections between the opposite end of said motor and feed operating member for transmitting rotation to the latter at a cutting speed including worms at opposite sides of said machine, and a variable speed mechanism between said worms.
18. In a mining machine, in combination, a motor, cutting mechanism driven from one end of said motor, a feed operating member adapted to cooperate directly with flexible feeding means and rotatable upon a horizontal axis extending longitudinally of the machine, and operative driving connections between the opposite end of said motor and feed operating member including a plurality of worms arranged respectively at opposite sides of said axis.
19. In a mining machine, in combination, a machine frame slidable on the mine bottom, a centrally located horizontal motor carried thereby having its axis extending longitudinally of the machine, cutting mechanism disposed at one end of said machine frame and driven by one end of said motor, a plurality of feed operating members disposed at the opposite end of said machine frame and adapted to cooperate directly with separate flexible feeding elements, and operative driv-

ing connections between the opposite end of 5 said motor and said feed operating members and disposed wholly at the end of said motor opposite from said cutting mechanism for transmitting rotation to the latter at a cutting speed including a plurality of worms and cooperating worm gears through which said feed operating members are driven.

20. In a mining machine, in combination, 10 a machine frame slidable on the mine bottom, a centrally located horizontal motor carried thereby having its axis extending longitudinally of the machine, cutting mechanism disposed at one end of said machine frame 15 and driven by one end of said motor, a plurality of feed operating members disposed at the opposite end of said machine frame rotatable on horizontal axes extending longitudinally of the machine, said feed operating 20 members being adapted to cooperate directly with separate flexible feeding elements, and operative driving connections between the opposite end of said motor and said feed operating members and disposed wholly at the end 25 of said motor opposite from said cutting mechanism for transmitting rotation to the latter at a cutting speed including a plurality of worms and cooperating worm gears through which said feed operating members 30 are driven.

21. In a mining machine, in combination, a machine frame slidable on the mine bottom, a centrally located horizontal motor carried by said frame and having its axis extending 35 longitudinally of the machine, cutting mechanism disposed at one end of said frame and driven by one end of said motor, a plurality of feed operating members disposed at the opposite end of said frame and each adapted 40 to cooperate directly with separate flexible feeding elements, and operative driving connections between the opposite end of said motor and said feed operating members and disposed wholly at the end of said motor 45 opposite from said cutting mechanism including a plurality of worms one of which rotates on an axis parallel to the axes of rotation of said feed operating members and worm gears meshing with said worms.

50. 22. In a mining machine, in combination, a machine frame slidable on the mine bottom, a centrally located horizontal motor carried by said frame and having its axis extending longitudinally of the machine, cutting mechanism 55 disposed at one end of said frame and driven by one end of said motor, a plurality of feed operating members disposed at the opposite end of said frame rotatable on horizontal axes extending longitudinally of the machine, said feed operating 60 members being each adapted to cooperate directly with separate flexible feeding elements, and operative driving connections between the opposite end of said motor and said feed operating members and disposed wholly at the end 65 of said frame and each adapted to cooperate directly with separate flexible feeding elements, and operative driving connections between the opposite end of said motor and said feed operating members and disposed wholly at the end of said motor opposite from said cutting mechanism for transmitting rotation to the latter at a cutting speed including a plurality of worms one of which is coaxial with said motor shaft and 70

of said motor opposite from said cutting mechanism including a plurality of worms one of which rotates on an axis parallel to the axes of rotation of said feed operating members and worm gears meshing with said 75 worms.

23. In a mining machine, in combination, a machine frame slidable on the mine bottom, a centrally located horizontal motor carried thereby and having its axis extending longitudinally of the machine, cutting mechanism driven by one end of said motor and disposed at one end of said machine frame, a plurality of feed operating members disposed at the opposite end of said frame and adapted to 80 cooperate directly with separate flexible feeding elements, and operative connections between the opposite end of said motor and said feed operating members and disposed wholly at the end of the motor opposite from 85 said cutting mechanism including a plurality of worms one of which rotates on a vertical axis and cooperating worm gears through which said feed operating members are driven. 90

24. In a mining machine, in combination, a machine frame slidable on the mine bottom, a centrally located horizontal motor carried thereby and having its axis extending longitudinally of the machine, cutting mechanism 95 driven by one end of said motor and disposed at one end of said machine frame, a plurality of feed operating members disposed at the opposite end of said frame rotatable on horizontal axes extending longitudinally of the machine, said feed operating members being adapted to cooperate directly with separate flexible feeding elements, and operative connections between the opposite end of said motor and said feed operating members and 100 disposed wholly at the end of said motor opposite from said cutting mechanism including a plurality of worms one of which rotates on a vertical axis and cooperating worm gears through which said feed operating 105 members are driven. 110

25. In a mining machine, in combination, a machine frame slidable on the mine bottom, a centrally located horizontal motor carried thereby having a power shaft extending longitudinally of the machine, cutting mechanism disposed at one end of said frame and driven by one end of said motor, a plurality of feed operating members disposed at the opposite end of said frame and each adapted to 115 cooperate directly with separate flexible feeding elements, and operative driving connections between the opposite end of said motor and said feed operating members and disposed wholly at the end of said motor opposite from said cutting mechanism for transmitting rotation to the latter at a cutting speed including a plurality of worms one of which is coaxial with said motor shaft and 120 125 130

cooperating worm gears through which said feed operating members are driven.

26. In a mining machine, in combination, a machine frame slidable on the mine bottom, a centrally located horizontal motor carried thereby having a power shaft extending longitudinally of the machine, cutting mechanism disposed at one end of said frame and driven by one end of said motor, a plurality of feed operating members disposed at the opposite end of said frame rotatable on horizontal axes extending longitudinally of the machine, said feed operating members being each adapted to cooperate directly with a separate flexible feeding element, and operative driving connections between the opposite end of said motor and said feed operating members and disposed wholly at the end of said motor opposite from said cutting mechanism for transmitting rotation to the latter at a cutting speed including a plurality of worms one of which is coaxial with said motor shaft and cooperating worm gears through which said feed operating members are driven.

27. In a mining machine, in combination, a machine frame slidable on the mine bottom, a horizontal motor carried by said frame, cutting mechanism carried by said frame and driven by said motor including a swingable cutter bar pivoted about a vertical axis at one end of said frame, a plurality of feed operating members rotatable on horizontal axes and disposed at the end of said frame remote from said cutter bar pivot and each adapted to cooperate directly with a separate flexible feeding element, and operative driving connections between said motor and said feed operating members and disposed wholly at the end of said frame remote from said cutting mechanism for transmitting rotation to said feed operating members at a cutting speed including a plurality of worms and cooperating worm gears through which said feed operating members are driven.

28. In a mining machine, in combination, a machine frame carried on the mine bottom, a horizontal motor carried by said frame, cutting mechanism carried by said frame and driven by said motor including a swingable cutter bar pivoted about a vertical axis at one end of said frame, a plurality of feed operating members rotatable on horizontal axes and disposed at the end of said frame remote from said cutter bar pivot and each adapted to cooperate directly with a separate flexible feeding element, and operative connections between said motor and said feed operating members and disposed wholly at the end of said frame remote from said cutting mechanism including a plurality of worms one of which rotates on an axis parallel to the axes of rotation of said feed operating members and worm gears meshing with said worms.

29. In a mining machine, in combination, a machine frame slidable on the mine bottom, a horizontal motor carried by said frame, cutting mechanism carried by said frame and driven by said motor including a swingable cutter bar pivoted about a vertical axis at one end of said frame, a plurality of feed operating members rotatable on horizontal axes and disposed at the end of said frame remote from said cutter bar pivot and each adapted to cooperate directly with a separate flexible feeding element, and operative connections between said motor and said feed operating members and disposed wholly at the end of said frame remote from said cutting mechanism including a plurality of worms one of which rotates on a vertical axis and cooperating worm gears through which said feed operating members are driven.

30. In a mining machine, in combination, a machine frame slidable on the mine bottom, a horizontal motor carried by said frame, cutting mechanism carried by said frame and driven by said motor including a swingable cutter bar pivoted about a vertical axis at one end of said frame, a plurality of feed operating members rotatable on horizontal axes and disposed at the end of said frame remote from said cutter bar pivot and each adapted to cooperate directly with a separate flexible feeding element, and operative driving connections between said motor and said operating members for transmitting rotation to the latter at a cutting speed including a plurality of worms one of which is coaxial with the motor axis and cooperating worm gears through which said feed operating members are driven.

31. In a mining machine, in combination, a machine frame slidable on the mine bottom, a horizontal motor carried thereby, cutting mechanism carried by said frame and driven by said motor including a swingable cutter bar pivotally mounted on a vertical axis at one end of said machine frame, a plurality of feed operating members rotatable on horizontal longitudinally extending axes and disposed on the end of said machine frame remote from said cutter bar pivot and each adapted to cooperate directly with separate flexible feeding elements, one of said flexible members cooperating with one of said feed operating members being adapted to swing said bar and the other flexible member being adapted to feed the machine at a cutting speed along the face, and operative driving connections between said motor and said feed operating members for transmitting rotation to the latter at a cutting speed including a plurality of worms and cooperating worm gears through which said feed operating members are driven.

In testimony whereof I affix my signature.
CHARLES F. OSGOOD. 130
